Patented Nov. 17, 1925.

UNITED STATES PATENT OFFICE.

JOHN PETERSON, OF MAYWOOD, ILLINOIS, ASSIGNOR TO COMBINATION BLOW TORCH MANUFACTURING COMPANY, OF MELROSE PARK, ILLINOIS, A CORPORATION OF ILLINOIS.

TORCH-SUPPORTED LADLE.

Original application filed June 24, 1921, Serial No. 480,017. Divided and this application filed February 8, 1924, Serial No. 691,372.

To all whom it may concern:

Be it known that I, JOHN PETERSON, a citizen of the United States, residing at Maywood, in the county of Cook and State 5 of Illinois, have invented certain new and useful Improvements in Torch-Supported Ladles, of which the following is a specification.

The present invention relates to ladles 10 for service as attachments to torches which emit a heating flame against the bowl of the ladle. One object of the invention is to so construct and mount the ladle that the flame will be emitted against the lower 15 part of the bowl where the solder or other contents must lie. To this end the support for the ladle lies above the outlet of the torch and the axis of the emitted flame extends in a direction parallel to and below 20 the supporting element which connects the ladle with the torch. Another object of the invention is to so mount the ladle bowl in its supporting element that it will be rotated automatically about a transverse 25 axis near the upper edge of the bowl as the torch is moved out of a horizontal position to various angular positions. This feature enables the ladle to be used to reach work in corners and other unhandy places where 30 solder or other substance must be applied to the material worked upon. With this construction the upper edge of the ladle bowl automatically remains horizontal and thus keeps the contents of the bowl from 35 spilling. The present invention will be best understood in all its features and advantages upon consideration of the following detailed description taken in connection with the accompanying drawing and the 40 scope of the invention will be particularly pointed out in the appended claims.

At the outset, it may be noted that the present application is a division of my prior application Serial No. 480,017, filed June 45 24, 1921, Patent No. 1,487,359, dated March 18, 1924.

In said drawing, Fig. 1 is an elevation of a portion of a torch and of a ladle constructed and arranged according to the 50 present invention to lie in the path of the flame emitted from the torch outlet, and Fig. 2 is a similar view of a modified ladle structure by which out of the way places may be reached in practice.

Referring to the drawing in detail, 10 55 designates the body of the torch, which is bored out so as to provide a central mixing and combustion chamber 11. The downwardly extending tubular shank 13 and an associated tube 14 connect the torch body 60 with its fuel supply tank 15. A pump is employed to force air into the tank 15 and thereby place the fuel, which is ordinarily gasoline, under pressure. A suitable passage 65 from the opening through shank 13 to the combustion chamber extends through the body of the torch and is controlled by a needle valve 19 secured to the forward end of valve rod 20 which is, in turn, provided at its rear end with an angularly 70 disposed handle 21. A fuel pan 30 is provided for holding a charge of fuel by which the torch is heated at starting. Air is supplied to combustion chamber 11 through the 75 holes 31. A finger piece 33 enables the torch to be readily handled. The torch construction is more fully illustrated and described in my aforesaid Patent No. 1,487,359 dated March 18, 1924.

As clearly shown, the ladles, constructed 80 and arranged in accordance with the present invention, are so positioned that the flame emitted from the torch impinges directly upon the bowl of the ladle. Two ladle constructions are shown. In the first instance the ladle, designated generally 75, has a bowl 81 and a connecting pin 41 which is in the nature of a handle. The bowl is secured to the outer end of the pin 41 and lies in a position to have its lower rounded 90 portion engaged by the flame emitted from the end of the torch. In this instance, the bowl has a projection 76 in the form of a boss which is bored out for the reception of the forward end of the pin 41, and a set 95 screw 77 passing through a threaded opening in the projection 76 engages the pin 41 to securely hold the parts together. In this instance, the ladle will be held from rotation and the torch and ladle may be 100 handled as a unit. This arrangement is advantageous where the torch is provided with a light fuel tank 15, and where the tank, torch and all are handled by the user as a single tool. In such case, the solder or other contents of the bowl 81, when heated, may be readily poured out 105 by the user merely picking up the whole

device and handling it as a single instrument.

Before passing to the next form of the invention it should be pointed out that the 5 rear end of the pin 41 extends into an opening in a boss 43 formed upon the body of the torch, and a set screw 44 serves to securely hold the pin in place. By the use of these parts the ladle 75 is firmly attached to 10 the torch 10 and, as noted, both ladle and torch may be used as a single instrument.

In some cases, notably in electric wiring, it may be desirable to employ a ladle which 15 will allow of certain movement of the torch, without changing the position of the solder or other substance in the bowl of the ladle. In such instance, a ladle of the type illustrated in Fig. 2 may be employed. This 20 ladle, designated generally as 78, has its bowl 82 pivotally mounted between the ends of a bifurcated arm 79 which extends outwardly as a permanent extension of the pin 41. With this construction the bowl 82 is 25 pivotally mounted so as to freely rotate about an axis passing through the pivotal points 80 located near the upper edge of the bowl. So long as the torch is moving about this axis, the ladle bowl will remain upright and its contents will not be spilled. 30 With this construction it is possible for an electric wire-man to get into corners and other out of the way places in order to dip the twisted ends of a wire joint into the solder contained in the ladle bowl or pot 82, 35 and thus make a soldered joint. Indeed, the arrangement may be used in any place

where the pot 82 can be brought underneath the wires to be soldered. Other uses will suggest themselves to persons working with solder and similar materials.

40

It will be seen that in carrying out my invention slight alterations may be made in the embodiments shown without departing from the spirit and scope of my invention.

What I claim as new and desire to secure 45 by a patent of the United States is:

1. The combination with a torch having a combustion chamber provided with an outlet through which the heating flame is adapted to pass, of a ladle having a bowl 50 provided with an exteriorly rounded bottom and lower portion, a bifurcated supporting arm pivotally secured at its forward bifurcated end to opposite portions of said bowl near its upper edge and connected at 55 its rear end to said torch at a point above said outlet, whereby the bowl will remain upright in various positions of the arm and torch and the emitted flame will play constantly in all said positions upon the rounded lower portion of said bowl.

2. In combination with a blow torch, a solder holding pot, a yoke affixed to the torch and extending adjacent the path of the flame, and pivotal bearings by which the 65 pot is suspended from said yoke in said path of the flame.

In testimony whereof, I hereunto subscribe my name this 4th day of February, A. D. 1924.

JOHN PETERSON.
